ELECTRIC GLOW DISCHARGE TUBE

Gilles Holst, Mari Johan Druyvesteyn, Jan Hendrik de Boer, and Marten Cornelis Teves, Eindhoven, Netherlands, assignors to Radio Corporation of America, a corporation of Delaware

Application February 18, 1931, Serial No. 516,546
In the Netherlands February 25, 1930

3 Claims. (Cl. 176—122)

This invention relates to an electric glow discharge tube. Tubes of this type having a gas or vapour filling and an independent discharge are used for various purposes, for example, as signal lamps and relays for translating electric current variations into light variations, as used in apparatus for receiving images transmitted telegraphically or by wireless.

With glow discharge tubes of this type frequently the drawback is prevalent that the tension at which the discharge is initiated, is rather high. This starting voltage is materially greater than the working voltage, i. e., the potential difference between the electrodes after the discharge has been initiated. It has been proposed already to reduce the starting and the working voltage by covering the cathode of the tube with an alkali metal.

The invention has for its purpose to reduce these voltages still further and in addition to improve other properties of the tubes.

The electric glow discharge tube according to the invention has an electrode containing an alkali metal which is provided on a layer of alkali metal oxide of the composition R_2O , in which R denotes an alkali metal. In this glow discharge tube not only the starting and the working voltage, but also the internal resistance are exceedingly low, whilst the electrode which is coated with alkali metal disintegrates but slightly. An additional advantage, which becomes particularly marked if the tube is used for receiving images, for example in television apparatus, consists in that the candle power per watt consumption, which is emitted by the luminous glow discharge, is material. By a proper choice of the gas filling the afterglow of such tubes, i. e. the continuation of the luminous discharge after the intensity of the current passing through the tube has been changed, may substantially entirely be avoided. Probably the afterglow of a glow discharge tube according to the invention which is filled, for example, with neon, lasts less than 0.00001 second.

The working and the starting voltage of the glow discharge may be reduced still further by using a gas filling constituted by a mixture of a gas, for example, neon, and another gas, for example, argon, whose ionization potential is smaller than the excitation potential of neon.

Furthermore the starting pressure of the glow discharge may be reduced to advantage by exposure of the electrode which is coated with alkali metal.

The invention will be more clearly understood by reference to the accompanying drawing, repre-

senting, by way of example, one embodiment of the invention.

The illustrated discharge tube which may be used as signal lamp, has a vitreous wall 1, to which a stem 2 is sealed, on which two electrodes 60 are mounted. One of these electrodes is constituted by a metal ring 3, which is carried by a supporting wire 4. The other electrode 5, which is carried by the supporting wire 6, is constituted by a plate made, for example, of copper. At the 65 side which is turned to the electrode 3, this plate is coated with a layer of caesium oxide of the composition Cs_2O , on which a layer of caesium is provided. If desired the other side of the plate, just as the supporting wires 4 and 6, may be 70 covered with an insulating material, for example, aluminum oxide.

Some methods of producing the surface of the cathode 5 will hereinafter be described.

After the electrodes have been mounted in the 75 tube and after the latter has been exhausted a small quantity of caesium may be introduced into the tube, which is deposited on the plate 5. The caesium may be introduced into the tube, for example, by evaporation from a vessel which 80 communicates with the glow discharge tube. A suitable method of introducing caesium into the tube, is described, for example, in the patent application 360,993 which issued as Patent No. 1,797,131. After the caesium has been introduced into the tube, oxygen is admitted in excess into the tube, so that the caesium is oxidized due to which Cs_2O_4 is formed. After the excessive quantity of oxygen has been removed from the tube, a fresh quantity of caesium is introduced 90 into the tube, by which the Cs_2O_4 is reduced so as to form Cs_2O . This reduction may be facilitated by heating to about 200° C. The Cs_2O formed may be recognized by its golden brown color. If the caesium is present in excess, it is 95 deposited on the Cs_2O formed. If the caesium is not present in excess, a fresh quantity of caesium is introduced into the tube, which is deposited on the layer of caesium oxide formed. Thereby the free caesium will be partly adsorbed 100 by the caesium oxide.

After the first introduction of the caesium it is also possible to admit a dosed quantity of oxygen into the tube, so that the caesium is oxidized so as to form Cs_2O , whereupon a fresh quantity 105 of caesium is introduced into the tube, which is deposited on the layer of caesium oxide formed.

Furthermore it is possible to cause the copper plate 5 to adsorb a water layer by introducing some water vapour into the tube. If caesium is 110

added in excess after the excessive water vapour has been removed from the tube, the caesium reacts with the water, whereby Cs_2O is formed and hydrogen is liberated which may be removed from the tube, whilst the excess of caesium is deposited on the caesium oxide layer formed.

Although in the methods described hereinbefore use is made of caesium it will be obvious that same may also be carried out in combination 10 with the other alkali metals.

After the cathode has been finished the tube is filled with a suitable gas or vapour filling. Satisfactory results have been obtained, for example, with a gas filling at a pressure of 8 millimetres 15 and constituted by neon and 0.2% of argon. The starting voltage of this tube, in which the distance between the electrodes may be assumed as being 8 millimetres, for example, will be found to be exceedingly low. When operating the tube 20 in the dark, a starting voltage of approximately 56 volts is all that will be required. By irradiating the cathode of the glow lamp by means of a light beam, whereby the exposure of the cathode was 0.015 lumen cm^2 the starting voltage was 25 54 volts, whereas the working pressure of the glow discharge tube appeared to be 37 volts.

When irradiating the glow lamp by means of a separate light source, it may be advisable to use the same light source for the irradiation of 30 several glow lamps. It is also possible to construct the light source and the glow lamp so as to form an aggregate.

Having now described our invention, what we 35 claim and desire to secure by Letters Patent is the following:

1. A method of operating glow discharge tubes having a pair of electrodes upon one of which is

a layer of alkali metal oxide which comprises applying a potential difference from a source across the tube electrodes and subjecting the alkali metal oxide electrode to light during the period when a potential difference is applied between said electrodes so as to reduce the striking potential of the tube.

2. An electric glow discharge tube comprising an annular anode electrode, a plate-like disk electrode serving as a cathode and arranged adjacent the anode and substantially of the same diameter as the opening in the annular anode electrode so that upon an application of an electric potential difference between the electrodes glow discharge takes place, and a coating of an alkali metal oxide of a composition R_2O , where R denotes an alkali metal, upon the surface of the disk-like cathode electrode adjacent the anode for reducing the striking potential.

3. An electric glow discharge tube having a cathode coated with an alkali metal of a composition R_2O , where R denotes an alkali metal, an annular anode electrode arranged coaxial with the cathode through which light from an external source may be applied to the cathode, and 100 a gaseous filling contained within the tube so that upon an application of a potential difference between the anode and cathode electrodes glow discharge is produced and the striking potential is decreased in accordance with the intensity of 105 light influencing the light sensitive portion of the cathode.
